UNITED STATES PATENT OFFICE.

FREDERICK J. SHANISEY, SR., OF CHICAGO, ILLINOIS, ASSIGNOR OF ONE-THIRD TO JOSEPH MILLER AND ONE-THIRD TO JOHN D. SULLIVAN, BOTH OF CHICAGO, ILLINOIS.

WINDOW-CLEANER.

1,278,036.

Specification of Letters Patent. Patented Sept. 3, 1918.

Application filed January 29, 1916. Serial No. 75,093.

To all whom it may concern:

Be it known that I, FREDERICK J. SHANISEY, Sr., a citizen of the United States, and a resident of the city of Chicago, county of 5 Cook, and State of Illinois, have invented certain new and useful Improvements in Window-Cleaners, of which the following is a specification.

My invention relates to improvements in window cleaning devices especially adapted for use in connection with automobiles, street cars, and other vehicles whereby the window in front of the driver of the vehicle may be readily and easily cleaned during operation 15 of the vehicle and without the necessity of the operator leaving his station.

The object of the invention is the production of a cleaning device as mentioned which will be of durable and economical construction, one which may be readily and easily attached to a window, and one which will be highly efficient in use. Other objects will appear hereinafter.

The invention consists in the combinations and arrangements of parts herein-after described and claimed.

The invention will be best understood by reference to the accompanying drawings forming a part of this specification, and in 30 which—

Figure 1 is an elevation of a window equipped with a cleaning device embodying the invention,

Fig. 2 is a section taken on line 2—2 of 35 Fig. 1,

Fig. 3 is a detail elevation of the cleaning device and a fragment of the window, the connecting bolt embodied in the construction being shown in section, and the washer plate at the adjacent side of the device being omitted,

Fig. 4 is a central section through the device with a fragment of the window shown in elevation,

Fig. 5 is a view similar to Fig. 1 showing a slightly modified form of the construction,

Fig. 6 is a section taken on line 6—6 of 45 Fig. 5, and

Figs. 7 and 8 are enlarged detail sections taken on lines 7—7 and 8—8 respectively of Fig. 6.

One form of the construction as illustrated in Figs. 1 to 4 inclusive comprises a pair of elongated arms 10 one of which is adapted 55 for arrangement upon each side of the

window 11 in connection with which the device is employed. The inner sides of arms 10 are lined with strips 12 of rubber or other suitable material adapted to contact with the window in order to effect cleaning thereof when the device is operated.

Corresponding ends of arms 10 are connected by means of a tubular pivot member 13 which passes loosely through a circular opening 14 which is formed in the window, as clearly shown in Figs. 2 and 4. The ends of pivot member 13 are reduced or cut away at opposite sides in order to form ears 15 which are adapted for engagement with elongated slots 16 which are formed in arms 10. With this arrangement it will be seen that said arms 10 are locked to the pivot member 13 against relative rotary movement, thus effecting a rigid connection between said arms whereby the same will move in unison upon rocking of either of said arms. Said arms are locked in engagement with the ends of pivot member 13 by means of a bolt 17 and corresponding thumb nut 18, washer plates 19 being interposed between the head of said bolt and said thumb nut for obvious reasons. When the parts are thus assembled, the ears 15 do not project entirely through the arms 10, there being an intervening space between the ends 85 of said ears and the washer plates 19, in order to allow for adjustment of said arms 10 toward each other by simply manipulating thumb nut 18, thus affording means for taking up any wear upon strips 12 during 90 use of the device.

The arm 10 which co-operates with the inner side of the window is equipped at its free end with a handle 20 whereby the arms 10 may be manually oscillated in order to 95 effect cleaning of the glass as will be readily understood.

The cleaner is of particular advantage in cold weather to prevent the gathering of frost upon the window or to readily remove the frost therefrom which may have gathered upon the window. The reason for this is that, with the construction set forth, by rapidly oscillating or rotating the arms 10, the friction produced by contact of the rubber strips with the window, will cause the latter to be heated and thus serve the function above mentioned. Also if desired the pivot of the arms 10 may be located midway the ends of said arms and in the center 110

of the window, in order to permit of complete rotary movement of said arms as may be desired.

The form shown in Figs. 5 to 8 inclusive is identical with that just described except that the outer ends of the cleaning arms 10' are of channel form, and the window engaging strips 12' are correspondingly formed, the arrangement being such that the 10 longitudinal edges of the members 12' contact with the window, thereby adapting said members 12' to more effectually clean the window. The cleaning members 12 and 12' are suitably secured to the arms with 15 which they co-operate, as for instance by cementing or by means of screws 21 as shown in Fig. 8.

While I have illustrated and described the preferred forms of construction for 20 carrying my invention into effect, these are capable of variation and modification without departing from the spirit of the invention. I, therefore, do not wish to be limited to the precise details of construction set 25 forth, but desire to avail myself of such

variations and modifications as come within the scope of the appended claim.

Having described my invention what I claim as new and desire to secure by Letters Patent is:

A cleaning device comprising a pair of arms adapted for engagement with opposite sides of a window; a pivot member adapted to extend through and rockingly engage with the window, and with the opposite 20 ends of which said arms engage; and a resilient covering for the inner side of each of said arms co-extensive therewith for engagement with the adjacent side of the window upon which the device is used, each 25 covering having an opening for the passage of the pivot member, substantially as described.

In testimony whereof I have signed my name to this specification in the presence of 45 two subscribing witnesses.

FREDERICK J. SHANISEY, Sr.
